(57) **ABSTRACT**

An automatic color mix dyeing process includes activating an automatic shaping device to shape an undyed object as a cylinder and tightening same; conveying the undyed object to a dyeing apparatus by means of spraying wherein the dyeing apparatus includes rows of spray devices, dye containers for containing dyes of different colors, each dye container being in fluid communication with the row of spray devices, a pump for moving the dyes in the dye containers to the rows of spray devices, and a control device for controlling the rows of spray devices to control a spray sequence, a spray time, and a spray quantity of dye; conveying the dyed object from the dyeing apparatus to a vapor device for color fixing wherein the dyed object is impregnated with hot vapor to obtain a finished object; cutting the tie ropes; and conveying, washing and drying the finished object.

13 Claims, 5 Drawing Sheets

FIG.1

FIG. 2

FIG.4

FIG.5

AUTOMATICALLY COLOR MIX DYEING PROCESS

BACKGROUND OF THE INVENTION

1. Field of the Invention

The invention relates to textile dyeing and more particularly to a dyeing process tied to a dyeing apparatus and a vapor device so that an undyed object such as one of strands of yarn, pieces of fabric, and garments can be dyed with different colors in one process.

2. Description of Related Art

Conventional dyeing processes include twisting dyeing (or cutting dyeing) for strands of yarn, bundle dyeing for fabric, and hanging dyeing for garments. The conventional dyeing processes are characterized by mixing dyes and water to form a solution in a tank, and immersing an undyed textile material in the tank for dyeing.

However, the conventional dyeing processes have the following disadvantages: The textile material is limited to cotton not polyester, nylon, etc. because only cotton can be dyed in a low temperature step and polyester and nylon are required to dye in a high temperature step. Only one color can be dyed on the textile material in one process. That is, a plurality of processes are required if multi-color textile products are desired. However, it can complicate the manufacturing process. Large quantity of water is required in the dyeing process. The used dye solution is harmful to the environment if sufficient treatment is not done prior to discharge.

Thus, the need for improvement still exists.

SUMMARY OF THE INVENTION

It is therefore one object of the invention to provide an automatic color mix dyeing process comprising the steps of activating an automatic shaping device to shape an undyed object as a cylinder and tightening same wherein the automatic shaping device has a spooling device configured to open or close and an automatic tying device; opening the spooling device to place the undyed object therein; passing the undyed object through the spooling device to shape as a cylinder; conveying the undyed object to the automatic tying device by a conveyor wherein the automatic tying device has a plurality of tie ropes controlled by a control device to tie the cylindrical undyed object in different intervals; conveying the shaped undyed object to a dyeing apparatus for dyeing by means of spraying wherein the dyeing apparatus includes a plurality of rows of spray devices, a plurality of dye containers for containing dyes of different colors, each dye container being in fluid communication with the row of spray devices, a pump for moving the dyes in the dye containers to the rows of spray devices, and the control device for controlling the rows of spray devices to control a spray sequence, a spray time, and a spray quantity of dye; conveying the dyed object from the dyeing apparatus to a vapor device for color fixing wherein the dyed object is impregnated with vapor of 110-160° C. in the vapor device for 5-10 minutes to obtain a finished object; conveying the finished object to a tie ropes removing device to cut the tie ropes; and conveying the finished object to a temporary storage device; wherein the plurality of rows of spray devices of the dyeing apparatus are able to simultaneously spray and dye on the undyed object to form multiple color mix patterns thereon in one dyeing process.

Preferably, after the step of conveying the finished object to a temporary storage device, further comprise the steps of washing and drying the finished object.

Preferably, the washing step is done by washing the finished object with a washing device to remove dyes left on surfaces of the finished object.

Preferably, the undyed object is one of strands of yarn, pieces of fabric, and garments.

Preferably, the control device includes a plurality of controllers, each for controlling the row of spray devices to control the spray sequence, the spray time, and the spray quantity of dye.

Preferably, the number of the rows of spray devices is six, and each row of spray devices has seven spray devices.

Preferably, a length from the dyeing apparatus to the temporary storage device via the vapor device along the conveyor is in the range between 15-20 meters.

Preferably, the rows of spray devices are spaced apart by a predetermined distance, and the distance is adjustable by the control device.

The invention has the following advantages and benefits in comparison with the conventional art:

The vapor device can impregnate the dyed object with vapor in a high temperature or low temperature step. For example, the dyed object is impregnated with vapor of 110-160° C. in the vapor device depending on the object such as strands of yarn, pieces of fabric, and garments. Specifically, the strands of yarn are of a material such as polyester, nylon, cotton, rayon, acrylic, or wool.

The dyeing apparatus comprises the control device including a plurality of controllers, each for controlling the row of spray devices to control the spray sequence, the spray time, and the spray quantity of dye. Thus, different colors can be dyed on the object to form different patterns thereon in one dyeing process, i.e., yield is increased.

The spray device can spray dyes on the undyed object and the vapor device can impregnate the dyed object with vapor to obtain a finished object. No water is used in the dyeing process. Thus, water cost is greatly decreased and it is environmentally friendly.

The above and other objects, features and advantages of the invention will become apparent from the following detailed description taken with the accompanying drawings.

BRIEF DESCRIPTION OF THE DRAWINGS

45 FIG. 1 is a flow chart of a dyeing process according to the invention;

FIG. 2 schematically depicts a dyeing apparatus according to the invention, the dyeing process being tied to the dyeing apparatus;

50 FIG. 3 is a perspective view of the spooling device being open;

FIG. 3A is a perspective view of the spooling device being closed;

55 FIG. 3B is a view similar to FIG. 3A showing a decrease of the diameter;

FIG. 4 is a photograph of pieces of first fabric dyed by the dyeing process of the invention; and

55 FIG. 5 is a photograph of pieces of second fabric dyed by the dyeing process of the invention.

DETAILED DESCRIPTION OF THE INVENTION

Referring to FIG. 1 to FIG. 5, a dyeing process and a dyeing apparatus in accordance with the invention are illustrated. The dyeing process comprises the following steps:

Placing an undyed object **20** on a conveyor **10**.

Activating an automatic shaping device **30** to shape the undyed object **20** as a cylinder and tightening same wherein the automatic shaping device **30** has a spooling device **32** configured to open or close and an automatic tying device **34**.

Opening the spooling device **32** to place the undyed object **20** therein.

Adjusting a diameter of the spooling device **32** to tighten or loosen the undyed object **20**.

Passing the undyed object **20** through the spooling device **32** to shape as a rope or cylinder.

Conveying the undyed object **20** to the automatic tying device **34** by the conveyor **10** wherein the automatic tying device **34** has a plurality of tie ropes **341** controlled by a control device **11** to tie the undyed object **20** in a interval of 5 to 20 cm, thereby fastening the flexibly shaped undyed object **20**; and the tie ropes **341** have different shapes and widths between 5 and 10 cm so that after dying the undyed object **20** different stripes are formed thereon, thereby forming different colors and patterns.

Conveying the shaped undyed object **20** to a dyeing apparatus **12** by the conveyor **10** for dyeing by means of spraying. The dyeing apparatus **12** includes a plurality of rows of spray devices **121**, a plurality of dye containers **122** for containing dyes of different colors, each dye container **122** being in fluid communication with the row of spray devices **121**, a pump **123** for moving dyes in the dye containers **122** to the rows of spray devices **121**; and the control device **11** including a plurality of controllers **112** each for controlling the row of spray devices **121** to control the spray sequence, the spray time, and the spray quantity of dye.

Conveying the dyed object **20** from the dyeing apparatus **12** to a vapor device **14** for color fixing wherein the dyed object **20** is impregnated with vapor of 110-160° C. in the vapor device **14** for 5-10 minutes to obtain a finished object.

Conveying the finished object to a tie ropes removing device **36** to cut the tie ropes **341** wherein the previously tied portions of the finished object will not be dyed, thereby rendering the finished object have different textures after the cut (see FIGS. 4 and 5).

Conveying the finished object to a temporary storage device **16**.

Washing the finished object with a washing device to remove dyes left on the surfaces of the finished object.

Drying the cleaned, finished object to obtain a finished object.

The conveyor **10** may be provided with a belt or a plurality of two opposing rollers.

As shown in FIGS. 2, 3A and 3B, the spooling device **32** may be flexed to adjust its diameter. Length **51** of the spooling device **32** is 30 cm and diameter **S2** thereof is between 5 and 30 cm. Shape of the undyed object **20** can be limited by adjusting the diameter **S2**. Thus, patterns of the undyed object **20** may have differences along a longitudinal direction after has been sprayed.

Preferably, the undyed object **20** is one of strands of yarn, pieces of fabric, and garments.

Preferably, length from the dyeing apparatus **12** to the temporary storage device **16** via the vapor device **14** along the conveyor **10** is in the range between 15-20 meters.

Preferably, the number of the rows of spray devices **121** is six, the rows of spray devices **121** are spaced apart by a predetermined distance, and the distance is adjustable by the control device, and each row of spray devices **121** has seven spray devices **121**.

It is envisaged by the invention that different colors can be dyed on the object to form different patterns thereon in one dyeing process.

The dyed fabric shown in FIGS. 4 and 5 are for illustrating the dyeing process of the invention not for limiting the dyeing process of the invention to be applicable to fabric.

While the invention has been described in terms of preferred embodiments, those skilled in the art will recognize that the invention can be practiced with modifications within the spirit and scope of the appended claims.

What is claimed is:

1. An automatic color mix dyeing process comprising the steps of:

activating an automatic shaping device to shape an undyed object as a cylinder and tightening same wherein the automatic shaping device has a spooling device configured to open or close and an automatic tying device;

opening the spooling device to place the undyed object therein;

passing the undyed object through the spooling device to shape as a cylinder;

conveying the undyed object to the automatic tying device by a conveyor wherein the automatic tying device has a plurality of tie ropes controlled by a control device to tie the cylindrical undyed object in different intervals; conveying the shaped undyed object to a dyeing apparatus

for dyeing by means of spraying wherein the dyeing apparatus includes a plurality of rows of spray devices, a plurality of dye containers for containing dyes of different colors, each dye container being in fluid communication with the row of spray devices, a pump for moving the dyes in the dye containers to the rows of spray devices, and the control device for controlling the rows of spray devices to control a spray sequence, a spray time, and a spray quantity of dye;

conveying the dyed object from the dyeing apparatus to a vapor device for color fixing wherein the dyed object is impregnated with vapor of 110-160° C. in the vapor device for 5-10 minutes to obtain a finished object;

conveying the finished object to a tie ropes removing device to cut the tie ropes; and

conveying the finished object to a temporary storage device;

wherein the plurality of rows of spray devices of the dyeing apparatus are able to simultaneously spray and dye on the undyed object to form multiple color mix patterns thereon in one dyeing process.

2. The automatic color mix dyeing process of claim 1, wherein after the step of conveying the finished object to a temporary storage device, further comprises the steps of washing and drying the finished object.

3. The automatic color mix dyeing process of claim 2, wherein the washing step is done by washing the finished object with a washing device to remove dyes left on surfaces of the finished object.

4. The automatic color mix dyeing process of claim 1, wherein the spooling device is configured to adjust its diameter by flexing to limit a shape of the undyed object passing through, and wherein the diameter is between 5 and 30 cm.

5. The automatic color mix dyeing process of claim 1, wherein the spooling device is cylindrical and configured to open.

6. The automatic color mix dyeing process of claim 1, wherein the tie ropes are of different shapes and wound

around the undyed object in different intervals, and wherein the intervals are between 5 and 20 cm.

7. The automatic color mix dyeing process of claim 1, wherein a width of each of the tie ropes is between 5 and 10 cm. 5

8. The automatic color mix dyeing process of claim 1, wherein the undyed object is one of strands of yarn, pieces of fabric, and garments.

9. The automatic color mix dyeing process of claim 1, wherein the control device includes a plurality of controllers, each for controlling the row of spray devices to control the spray sequence, the spray time, and the spray quantity of dye. 10

10. The automatic color mix dyeing process of claim 1, wherein the number of the rows of spray devices is six, and 15 each row of spray devices has seven spray devices.

11. The automatic color mix dyeing process of claim 1, wherein a length from the dyeing apparatus to the temporary storage device via the vapor device along the conveyor is in the range between 15-20 meters. 20

12. The automatic color mix dyeing process of claim 1, wherein the rows of spray devices are spaced apart by a predetermined distance, and the distance is adjustable by the control device.

13. The automatic color mix dyeing process of claim 1, 25 wherein the conveyor is provided with a belt or a plurality of two opposing rollers.
